UNITED STATES PATENT OFFICE.

FRANK MALOCSAY, OF NEW YORK, N. Y., ASSIGNOR TO SONORA PHONOGRAPH CORPORATION, A CORPORATION OF NEW YORK.

STOP MECHANISM FOR TALKING-MACHINES.

1,277,449.

Specification of Letters Patent.

Patented Sept. 3, 1918.

Application filed September 21, 1915. Serial No. 51,886.

To all whom it may concern:

Be it known that I, FRANK MALOCSAY, a citizen of the United States, residing in the borough of the Bronx, county of Bronx, city and State of New York, have invented certain new and useful Improvements in Stop Mechanism for Talking-Machines, of which the following is a specification.

My invention relates to talking machines of the type known as disk record machines, and is of the same general type as the device shown in my co-pending application, Serial No. 879,865, filed December 31, 1914.

The object of my present invention is to simplify the construction of the before mentioned apparatus, and to produce a device which will operate on disk records which do not run true.

A further object is to so construct the device that it will have fewer operating parts, and will be more positive in its actions.

A further object is to so construct and proportion the parts that while the operator is placing the sound-box in position to produce, the turn-table may travel while the tone-arm is not traveling across the record groove.

These and further objects will more fully appear in the following specification and accompanying drawings considered together or separately.

My invention is illustrated in the accompanying drawings, in which similar reference characters designate corresponding parts in all of the figures, and in which,

Figure 1 is a plan view of a disk record talking machine embodying my invention, the cover being removed and with parts broken away;

Fig. 2 is a front elevation of the same with a portion of the casing removed;

Fig. 3 is a plan view of the operative parts of the device, the tone-arm being omitted, the brake being shown out of engagement with the turn-table;

Fig. 4 is a similar view showing the brake applied to the turn-table;

Fig. 5 is a horizontal section showing the parts in position for the preliminary rotation of the turn-table;

Fig. 6 is a section on the line 6—6 of Fig. 3;

Fig. 7 is a section on the line 7—7 of Fig. 3; and

Fig. 8 is a sectional view of a portion of 55 a disk record tablet.

In the drawings, 1 represents a cabinet in which is carried the usual motor and sound amplifying device, and having its front panel provided with openings through 60 which the sound may be conveyed to the atmosphere. The cabinet is provided with a horizontal partition 2, and a cover (not shown). The shaft 3 of the motor projects through the shelf and carries a turn-table 65 4, upon which is supported a record disk 5. The disk has upon its face the usual spiral record groove 6. At the outer end of the groove 6 a safety groove 7 is provided. This groove is concentric with the center 70 of the motor shaft 3. A similar safety groove 8 is impressed, cut, or engraved on the surface of the disk at the inner end of the record groove.

Pivoted so as to swing horizontally across 75 the record disk, is a tone-arm 9, on the outer end of which is the usual sound-box 10, carrying a stylus or reproducer of a suitable type.

Secured to the partition 2 is a bed plate 80 11, on which most of the operating parts of the device are located. The motor shaft 3 projects through the bed plate, and pivoted on the plate at 12 is a lever 13. This lever rests upon the base plate, and is provided 85 with an opening 14, which surrounds the motor shaft and permits movement of the shaft relatively thereto. Carried on the motor shaft is a spur wheel 15, which is in mesh with a similar spur wheel 16, carried 90 on a stud-shaft 17 on the lever 13. The stud-shaft is provided with a spur pinion 18, which is in mesh with a gear 19, carried on a stud 20 on the lever 13. Rigidly secured to the gear 19 is a cam 21. A 95 second cam 22 is similarly secured to the gear. The gears 15 and 16 are of the same pitch diameter, and the pinion 18 and gear 19 have a ratio of 1 to 3. The cams 21 and 22 will therefore rotate at one-third of the 100

speed of the motor shaft, and in the same direction.

Secured to the tone-arm by means of a clamp is an arm 23, the outer end of which forms an open yoke 24. Loosely carried on the outer bow of the yoke is a slide 25, the upper surface of which is recessed to permit the passage of a swinging arm 26. The arm 26 is loosely pivoted to the bed plate, and when in operative position, extends in a direction toward the center of the stud 20. The recess in the top surface of the slide 25 is wider than the arm 26, to allow for movement of the arm relatively to the slide. The arm 26, approximately midway between its pivot and extreme end, is provided with a depending pin 27, which extends down nearly to the bed plate. The free end of the arm rests on a bridge 28 also carried by the plate.

Carried by the bed plate, and in line with the center line of the arm 26 when the latter is in operative position, is a slide 29. One end of the slide is provided with a V shaped notch 30 which is adapted to engage the pin 27 and center the arm 26. The opposite end of the slide is rounded, and is held in yielding engagement with the cam 21 on the stud 20, by means of a spring 29^a.

Pivoted at 31 to the bed plate, is a finger 32. The free end of the finger is spring-pressed against the cam 22 by means of the spring member 31^a. A projection 33 on the free end of the finger is adapted to lie in longitudinal alinement with the center line of the arm 26 when the latter is in operative position.

The free end of the lever 13 is provided with a finger 34, which engages a trigger 35 carried on the short end of a lock lever 36. The lock lever is pivoted at 37 to the partition 2, and is provided with a finger 31 and a handle 52. The lever 13 is held with the cam 22 in engagement with the finger 32 by means of a spring 38, and the lever 36 and trigger 35 are held in engagement with the finger 34, by means of a spring 39. The trigger 35 is pivoted to the short end of the lever 36, and has one arm 40 notched for engagement with a pin 41, carried on a ratchet wheel 42, which in turn is mounted on the bed plate 11. A spring pressed pawl 43, carried on an angle lever 44, engages the ratchet wheel 42, and rotates the same. One arm 45 of the angle lever is held by a spring 46 in engagement with the cam 22.

In the embodiment of the invention illustrated, the ratchet wheel 42 is provided with 23 teeth, one of which, 47, is of double length, so that when the pawl 43 rests in the space 48, it will not, by the operation of the angle lever, feed the ratchet wheel forward.

Mounted on the partition 2, adjacent to the periphery of the turn-table, is a hand

lever 48 which carries a brake shoe 49. A spring 50 engages the lever and tends normally to hold the brake shoe in engagement with the turn-table and prevent rotation of the same.

On the upper surface of the slide, and covering the recess, is a keeper plate 53. This plate is normally out of contact with the arm 26, but prevents its accidental removal from the recess during transportation. A stop 54 is carried by the shelf 2 at each side of the slide to prevent too great movement thereof.

I have shown the record disk with two safety grooves 7 and 8. These grooves are produced in the manufacture of the disk and define the space on which the spiral record groove is to be impressed. But one of the safety grooves,—that at the end of the record groove,—is necessary to the operation of the device, but as in disks turned out by some manufacturers, have the record groove beginning at the inside and working outward, and others have the groove beginning at the outside and working in, I prefer to have the two safety grooves in the disk, so that it can be used with either style of record groove. It will be understood that the invention may be carried out without the use of the safety groove, for the reason that without the safety groove, when the stylus reaches the end of the record groove, it will run upon the flat surface of disk, and the feed of the tone-arm will cease.

The operation is as follows:

When the rotation of the turn-table has been arrested by the application of the brake, the parts will be in the position shown in Fig. 4. The stylus is raised from contact with the disk by throwing the sound-box back on the tone-arm, which is then swung to a position in which it will not be above the disk. The played disk will now be removed from the turn-table, and a new one substituted. The handle of the lever 48 will be moved to the right, the brake shoe will release the turn-table, which will begin to rotate. The finger 31, of the lever 13, will be moved, by the spring 39 to engage the brake shoe and retain it in position away from contact with the turntable, as shown in Figs. 1 and 3. The train of gears 15, 16, 18 and 19, will be set in motion, together with the cams 21 and 22. The cam 22 will engage the arm 45, and tilt the lever 44, which will cause the pawl 43 to feed the ratchet wheel 42, one tooth for each rotation of the cam 22. At each rotation of the same cam, the finger 32 will be moved into engagement with the swinging arm 26 which is centered at each revolution of the cam 21, which moves the slide 29, so that its notched end brings the swinging arm to its central position. When the projection 33 strikes the end of the swinging arm, the lever 13

will be swung in a direction away from the swinging arm, and the finger 34 will engage the lever 35 and cause it to swing on its pivot.

5 While the above described operation is going on, the operator is swinging the tone-arm to a position over the disk, and the arm 23 in position below the turn-table, and swinging the sound-box down to bring the 10 stylus in contact with the record groove. By the time this has been accomplished, the ratchet wheel 42 will have made a complete revolution, and the pawl 43 will rest in the long space 47, and as the throw of the lever 15 44 is not sufficient to cause the pawl to travel far enough to engage the next tooth, the rotation of the ratchet will cease, while the action of the lever continues. The pin 41 of the ratchet will now have engaged the notch 20 in the arm 40 of the trigger 35, and the latter is locked against movement relatively to the lever 36. While the ratchet wheel 42 is being rotated by the engagement of the pawl 25 43 with the short teeth the trigger 35 will be out of the path of the finger 34 and the movements of the lever 13 when the finger 33 and arm 26 engage will not be communicated to the lock lever 36 and the brake shoe will remain in engagement with the turntable 30 while the tone-arm is being set in its neutral position.

As the tone-arm 9 and yoke 24 are fed across the line of the spiral record groove by the engagement of the stylus with the 35 record groove, the frictional engagement of the slide 25 with the yoke will move it, the slide, in the direction of the travel of the tone-arm, and the slide will engage the swinging arm and cause it to swing in the 40 same direction. The slide 29 will be moved against the tension of its spring 29^a at each revolution of the cam 21, and the V shaped notch 30 in its end will engage the pin 27 and swing the arm, and with it the slide, 45 back to the central position of the arm. As soon as the greater diameter of the cam 21 leaves the end of the slide, the latter, under the influence of its spring, will recede from its point of engagement with the pin 27, and 50 the swinging arm will be swung to one side by the frictional engagement of the slide with yoke. The high part of the cam 22 will now engage the finger 32, and move the projection 33 toward the end of the swinging arm, the path of the projection being 55 in line with the central position of the arm, but as the arm has been swung to one side, the projection will not engage it.

When, however, the feed of the tone-arm 60 and yoke have been arrested by the stylus passing out of the record groove, and when the swinging arm 26 has been centered, by the engagement of the slide 29 with the pin 27, it will remain in that position, and when 65 the projection 33 is again moved outward,

by the engagement of the cam 22, the lever 13 will be swung away from the swinging arm, the finger 34 will engage the lever 35 and, as that lever is locked against independent movement by its engagement with the pin 41, the lever 36 will be swung on its pivot 37, the finger 51 will be withdrawn from contact with the brake shoe, the spring 50 will throw the lever 48, the brake shoe will engage the turntable, and the rotation 70 of the machine will be arrested. When the lever 36 is swung, as above described, the ratchet wheel 42 will be given a partial revolution by the engagement of the arm 40 with the pin 41. This will move the ratchet 75 wheel a distance sufficient to remove the pawl 43 from the long space 47, and into engagement with a tooth back of it. This will leave the mechanism in position shown in Fig. 4 in readiness to operate, as before. 80 85

In accordance with the provisions of the patent statute, I have described the principle of my invention together with the apparatus which I now consider to represent the best embodiment thereof, but I desire to 90 have it understood that the apparatus shown is merely illustrative, and that the invention can be carried out in other ways without departing from the spirit of my invention.

Having now described my invention, what 95 I claim as new and desire to secure by Letters Patent of the United States, is as follows:

1. In a talking machine, the combination with a rotating element and a brake therefor, 100 of a member movable across the path of rotation of the element, an arm moved by the member, a lever, a rotating element carried by the lever, a finger operated by the rotating element, a brake holding device, means 105 for moving the lever to operate the device to release the brake when the arm and finger are in a predetermined position, a second lever coöperating with the rotating element, and means operatable by the second lever for 110 enabling the first mentioned lever to be operated without causing the brake to be applied. 115

2. In a talking machine, the combination with a rotating element and a brake therefor, 120 of a member movable across the path of rotation of the element, an arm moved by the member, a lever, a rotating element carried by the lever, a finger operated by the rotating element, means for moving the arm in a direction opposite to that of the movement of the member, a brake holding device, means for moving the lever to operate the device to release the brake when the arm and finger are in a predetermined position, a second lever coöperating with the rotating element, and means operatable by the second lever for 125 enabling the first mentioned lever to be operated without causing the brake to be applied. 130

3. In a talking machine, the combination with a rotating element and a brake therefor, of a member movable across the path of rotation of the element, an arm moved by the member, a lever, a rotating element carried by the lever, a finger operated by the rotating element, a slide for moving the arm in a direction opposite to that of the movement of the member, a brake holding device, means for moving the lever to operate the device to release the brake when the arm and finger are in a predetermined position, a second lever co-operating with the rotating element, and means operatable by the second lever for enabling the first mentioned lever to be operated without causing the brake to be applied. 70

4. In a talking machine, the combination with a rotating element and a brake therefor, of a member movable across the path of rotation of the element, an arm moved by the member, a lever, a rotating element carried by the lever, a finger operated by the rotating element, a slide for moving the arm in a direction opposite to that of the movement of the member, said slide being movable by engagement of the rotating element, a brake holding device, means for moving the lever to operate the device to release the brake when the arm and finger are in a predetermined position, a second lever co-operating with the rotating element, and means operatable by the second lever for enabling the first mentioned lever to be operated without causing the brake to be applied. 80

5. In a talking machine, the combination with a rotating element, and a brake therefor, means for applying the brake, of a member movable across the path of rotation of the element, a slide carried by the member, a pivoted arm resting on the slide, and movable therewith, a master lever, a brake holding device, said device engaging the master lever, a rotating element carried by the master lever, a pivoted finger engaging the element and movable thereby to engage the arm when the latter is in a predetermined position, and swing the master lever and brake holder to release the brake, a trigger carried by the brake holder, means for holding the trigger in the path of the master lever to move the brake holder, and means for moving the trigger relatively to the brake holder to allow the master lever to move without applying the brake. 90

6. In a talking machine, the combination with a rotating element, and a brake therefor, means for applying the brake, of a member movable across the path of rotation of the element, a slide carried by the member, and frictionally engaging the latter, a pivoted arm resting on the slide and movable therewith, a master lever, a device for holding the brake in inoperative position, said device engaging the master lever, a rotating element carried by the master lever, a pivoted finger engaging the element and movable thereby to engage the arm when the latter is in a predetermined position, and swing the master lever and brake holder to release the brake, a trigger carried by the brake holder, means for holding the trigger in the path of the master lever to move the brake holder, and means for moving the trigger relatively to the brake holder to allow the master lever to move without applying the brake. 100

7. In a talking machine, the combination with a rotating element, and a brake therefor, means for applying the brake, of a member movable across the path of rotation of the element, a slide carried by the member, stops for limiting the movement of the slide, a pivoted arm resting on the slide, and movable therewith, a master lever, a device for holding the brake in inoperative position, said device engaging the master lever, a rotating element carried by the master lever, a pivoted finger engaging the element and movable thereby to engage the arm when the latter is in a predetermined position, and swing the master lever and brake holder to release the brake, a trigger carried by the brake holder, means for holding the trigger in the path of the master lever to move the brake holder, and means for moving the trigger relatively to the brake holder to allow the master lever to move without applying the brake. 110

8. In a talking machine, the combination with a rotating element, and a brake therefor, of a member movable across the path of rotation of the element, a slide carried by the member, stops for limiting the movement of the slide, a pivoted arm resting on the slide, and movable therewith, a bridge for retaining the arm in position, a master lever, a brake holding device engaging the master lever, a rotating element carried by the master lever, a pivoted finger engaging the element and movable thereby to engage the arm when the latter is in a predetermined position, and swing the master lever and brake holder, means for holding the trigger in the path of the master lever to move the brake holder, and means for moving the trigger relatively to the brake holder to allow the master lever to move without applying the brake. 120

9. In a talking machine, the combination with a rotating element, and a brake therefor, means for applying the brake, of a member movable across the path of rotation of the element, an arm moved by the member, a lever, a rotary element carried by the lever, a finger operated by the rotary element, means for moving the lever and releasing the brake when the arm and finger are in a pre-determined position, a second lever co- 130

- operating with the rotary element, a brake lever for holding the brake inoperative, and a trigger carried thereby, said trigger co-operating with the first mentioned lever, a 5 ratchet wheel, a pawl on the second mentioned lever engaging the ratchet wheel, said ratchet wheel having a blank space in which the pawl rests, and means carried on the trigger for rotating the ratchet wheel.
- 10 10. In a talking machine, the combination with a rotating element, and a brake therefor, means for applying the brake, of a member movable across the path of rotation of the element, an arm moved by the member, 15 a lever, a rotary element carried by the lever, a finger operated by the element, means for moving the lever and means for applying the brake when the arm and finger are in a pre-

determined position, a second lever co-operating with the element, a brake lever, and a 20 trigger carried thereby, said trigger co-operating with the first mentioned lever, a ratchet wheel, a pawl on the second mentioned lever, engaging the ratchet wheel, said ratchet wheel having a blank space in 25 which the pawl rests, means carried on the trigger for rotating the ratchet wheel, and means for disconnecting the trigger and ratchet wheel.

This specification signed and witnessed 30 this 14th day of September, 1915.

FRANK MALOCSAY.
